UNITED STATES PATENT OFFICE

LLOYD STEARMAN, OF WICHITA, KANSAS, ASSIGNOR TO THE STEARMAN AIRCRAFT COMPANY, INC., OF WICHITA, KANSAS, A CORPORATION OF KANSAS

AIR-INTAKE HEATER

Application filed September 12, 1929. Serial No. 392,063.

The objects of this invention are to provide a simple, practical and efficient air intake for aircraft engines, which may be used to heat the air or not, as required; which will automatically guard against fire from motor "back fire" and which, furthermore, will be in such a form as to be readily applicable to existing aircraft.

The foregoing and other desirable objects are attained by certain novel features of construction, combinations and relations of parts as hereinafter set forth and broadly covered in the claims.

The drawings accompanying and forming part of this specification illustrate one of the commercial embodiments of the invention, but as this illustration is primarily for purposes of disclosure, it should be understood that the structure may be modified in various respects without departure from the true spirit and broad scope of the invention.

Figure 1 is a broken side elevation and part sectional view illustrating application of the invention to an airplane.

Figure 2 is a front view as taken on substantially the plane of line 2—2 of Figure 1.

Figure 3 is an enlarged broken plan view illustrating particularly the arrangement of the heater with respect to the exhaust pipes.

Figure 4 is a broken sectional view as on substantially the plane of line 4—4 of Figure 3.

In Figures 1 and 2, the fuselage frame of an airplane is indicated at 5, the cowling being shown by the broken lines 6 and the motor at 7 exhausting into pipes 8 beneath and extending rearwardly at the sides of the body. The carburetor of the motor is indicated generally at 9, located in rear of the motor, within the cowling, and having an air intake at the bottom.

The control and heating of the intake air is effected by an uptake 10, flanged at 11 to match the air intake in the bottom of the carburetor and having branches 12 entered in the opposite sides of the same, said branches extending from the "stoves" or heating chambers 13 surrounding the exhaust pipes, said stoves having conduits 14 opening into the rear end of a box or casing 15, carrying on

top, the forks or branches 16 from which the risers 17 extend up through the top cowling. These risers form separate air intakes and usually extend a slight distance up above the outer cowling, opening forward on an incline 55 such as shown in Figures 1 and 2, to operate when the ship is in flight, as "scoops" to force the air into the carburetor. An advantage in taking the air in at the top of the machine is that it is freer of dust, an important 60 feature when the machine is on the ground.

The air passing down the pipes 17 into the top of the distributor box 15 may be either passed forwardly directly into the carburetor intake or be forced to pass through the heaters before it reaches the carburetor. This control is accomplished by a damper or swing gate 18, pivoted at 19 in the box or casing 15, with its upper edge operating in the chamber 20 in the top of the casing beneath the 70 entrance of the downtake pipes. This swing valve is shown as controlled by a lever 21 on the protruding end of the pivoting shaft 19, said lever being operated by suitable linkage or control connections taken to a point within 75 reach of the pilot.

With the valve or vane 18 in the position shown in full lines in Figures 3 and 4, it will be seen that the air arriving by downtakes 17 will be forced to travel rearwardly in the box 80 15 and by the transverse conduits 14 to the air heating chambers 13, passing from the forward ends of these chambers through transverse conduits 12 into the forward portion of the box 15, the uptake 10 and so into 85 the carburetor intake. When the vane is swung rearwardly, as indicated in the broken lines, passage to the back is cut off, and the air is sent forwardly directly into the uptake and hence into the carburetor without the 90 preheating last described. Thus, the pilot at will, may preheat or supply the air to the carburetor without pre-heating.

To release "back fire" explosions of the engine and to prevent such explosions from 95 starting fire within the cowling, an automatic vent and exhaust discharge is provided in the form of a downwardly directed conduit 22, substantially a downward continuation of the uptake 10, opening outside 100

the cowling 6, as indicated in Figures 1 and 4, and closed normally by a rearwardly slanting trap door 23 hinged at its forward edge at 24 and held normally closed by a spring 25. As the suction of the motor is normally exerted against this trap door, the spring 25 may be relatively weak so as to readily yield to the force of a back fire through the muffler intake. Thus, the danger of starting a fire within the machine from back firing of the engine, is practically eliminated.

10 The apparatus is relatively small and compact and fits into the ordinarily unoccupied space beneath and just to the rear of the carbureter. The box portion of the device is supported by the transverse piping at the front and rear ends of the same, forming bridges between the stoves on the exhaust pipes. The downtakes carry air from outside and above the machine directly into the intermediate portion of the box and the swing valve sends this air either directly up into the carbureter or indirectly, through the stoves, into the carbureter.

15 20 25 The various parts of the device may all be made of relatively light sheet metal. The generally rectangular form of the air box gives it the desired strength and enables the same to occupy a relatively small space in 30 between the two air heaters. This air box is protected within the lower cowling of the machine and the transverse pipes 12, 14 extend through such cowling to the stoves on the exhaust pipes outside the cowling.

35 What is claimed is:

1. An air intake heater for aircraft, comprising in combination with the fuselage and engine structures, an air heating chamber, a box connected at opposite ends with said air heating chamber and connected at one end with the air intake for the engine, an air intake extending from outside the upper portion of the fuselage to an intermediate portion of the box and valve means in said box for forcing the intaken air through the heating chamber to the engine or for sending such air directly to the engine.

2. In combination with the fuselage and engine structures of an airplane, conduit means forming a chamber connected with the air intake of the engine, an air intake opening into said conduit means from a point outside the fuselage, an air heater connected with said conduit means and valve mechanism in said conduit means for directing the intaken air to the engine air intake or through the air heater to said engine air intake.

3. In combination with the fuselage and engine structures of an airplane, conduit means forming a chamber connected with the air intake of the engine, an air intake opening into said conduit means from a point outside the fuselage, an air heater connected with said conduit means and valve

mechanism in said conduit means for directing the intaken air to the engine air intake or through the air heater to said engine air intake, said conduit means having a back fire discharging vent opening outside the fuselage and a pressure actuated yielding closure for said vent.

4. In apparatus of the character disclosed, the combination of engine exhaust pipes having stoves thereon, a distributor box located between said stoves and having transverse conduits at opposite ends of the same in connection with said stoves, said box having a part at one end for connection with the air intake of an engine carbureter, an air intake conduit opening into the box intermediate the ends of the same and valve mechanism for directing intaken air toward one or the other end of said box.

5. In apparatus of the character disclosed, the combination of engine exhaust pipes having stoves thereon, a distributor box located between said stoves and having transverse conduits at opposite ends of the same in connection with said stoves, said box having a part at one end for connection with the air intake of an engine carbureter, an air intake conduit opening into the box intermediate the ends of the same and valve mechanism for directing intaken air toward one or the other end of said box, said box having a vent in the bottom of the same in line with the carbureter intake portion and a closure for said vent yieldable to internal pressure in the vent.

6. In combination with an airplane fuselage and engine having a carbureter intake, an air intake extending up through the upper cowling of the fuselage and opening forwardly in the direction of airplane travel, an air heater, conduit means connected with said air intake and with said air heater, said conduit means having provision for connection of the same with the carbureter intake of the engine and means controllable to send the intaken air directly into the carbureter intake, or indirectly through the air heater into the carbureter intake.

7. In combination with an airplane fuselage and engine having a carbureter intake, an air intake extending up through the upper cowling of the fuselage and opening forwardly in the direction of airplane travel, an air heater, conduit means connected with said air intake and with said air heater, said conduit means having provision for connection of the same with the carbureter intake of the engine and means controllable to send the intaken air directly into the carbureter intake, or indirectly through the air heater into the carbureter intake, said conduit means having a vent opening through the cowling of the fuselage and a pressure operable yieldable closure for said vent.

8. In combination, an air box having a

- neck portion for connection with a carbureter intake, said air box having means at opposite ends of the same for enabling connection with an air heater and having means intermediate its ends for enabling the connection of an air intake and a swing valve mounted in said air box opposite said air intake for directing intaken air toward one end or the other of the air box.
9. In combination, an air box having a neck portion for connection with a carbureter intake, said air box having means at opposite ends of the same for enabling connection with an air heater and having means intermediate its ends for enabling the connection of an air intake and a swing valve mounted in said air box opposite said air intake for directing intaken air toward one end or the other of the air box, said air box having a vent opposite the carbureter intake connection portion and a spring closed trap door for normally holding said vent closed.

In testimony whereof I affix my signature.
LLOYD STEARMAN.
